UNITED STATES PATENT OFFICE

2,564,711

VENT FOR FLOATING ROOF TANKS

Frederick D. Moyer and John W. Allen, Chicago,
Ill., assignors to Chicago Bridge & Iron Com-
pany, a corporation of Illinois

Application June 2, 1945, Serial No. 597,248.

2 Claims. (Cl. 220—26)

1

This invention relates to a vent for a liquid storage tank, and relates particularly to a vent for a floating roof tank.

It has been found that where extremely volatile liquids are to be stored in large quantities, it is desirable to build the storage tanks with floating roofs, so that the space between the top of the liquid and the top of the tank is small at all times. By keeping this space small it is found that the volatile liquids are less subject to evaporation losses. The floating roof floats on top of the liquid in the tank, and is provided with a frictional seal between the roof and the sides of the tank. In this construction when the tank is full the roof will be up near the top of the tank. Then as the tank is emptied the roof lowers, thereby keeping at all times substantially the same small space between the top of the liquid and the roof of the tank. Because the liquids in a tank of this type are usually quite volatile, the space above the liquid is sometimes under pressure higher than atmospheric pressure caused by evaporation of the liquid. Then at other times this space is under vacuum or at pressure lower than atmospheric pressure. In order to relieve the pressure and vacuum in the tank it has been proposed to provide a vent that will automatically correct these conditions.

The vents that were proposed in the past were oftentimes of complex construction and had several moving parts that were subjected to wear. Many of the vents used liquid sealing material that had to be renewed from time to time, and it sometimes happened that condensate from the tank froze up and made the vent non-operative. There has never been a completely satisfactory vent that was automatic in operation and that required a minimum of care and attention. The new vent which is the subject of this invention overcomes the objections of the old type vents in that it is of very simple construction, provides automatic sealing of the contents of the tank, and is completely non-freezing. The new vent has only one moving part, which is a freely rising cup, and thus requires a very minimum of service and attention. There are no valve seats, and the liquid in the tank provides the only liquid seal necessary. The new vent has a positive action for both pressure and vacuum.

The new vent which we have invented is mounted on the floating portion of a floating roof liquid storage tank where pressure and vacuum in the tank cause the roof to rise and fall respectively. This vent comprises broadly a pipe submerged in the liquid in the tank and

2

having one end open to the atmosphere and the other end open to the interior of the tank above the highest liquid level. Over the interior end of the pipe there is positioned an inverted cup that is free to move relative to the pipe but is prevented from ever completely closing the end of the pipe. The vent, being mounted on the roof, rises and falls with the roof under the forces of pressure and vacuum within the tank.

The invention will be described as related to the typical embodiment of the same shown in the accompanying drawings. Of the drawings, Fig. 1 is a plan view of the new vent attached to the roof of a floating roof tank; Fig. 2 is a section elevation taken along line 2—2 of Fig. 1; Fig. 3 is an end elevation of the vent; Fig. 4 is a horizontal section taken along line 4—4 of Fig. 2; and Fig. 5 is a section taken along line 5—5 of Fig. 2.

The new vent shown in the accompanying drawings includes a U-shaped pipe 10 mounted in inverted position in the roof of the tank with one end 11 of the pipe extending above the roof and the other end 12 of the pipe below the roof. The confined end 12 of the pipe is positioned so that at all times it is above the liquid level within the tank. On the open end 11 of the pipe there is positioned a loosely fitting cap 13 to prevent rain from falling into the open end. This cap is supported on radial bars 14 fastened to the pipe, and is hingedly mounted so that it may be readily removed for cleaning purposes. Between the cap 13 and the pipe there is located a screen 15 to prevent dirt and other foreign bodies from entering the open end 11 of the pipe. On the confined end 12 of the pipe there is mounted a cylindrical housing 16 that extends above the roof of the tank. Within the housing and over the end of the pipe there is positioned an inverted cup 17 normally resting on the bottom of the cylindrical housing 16. The housing has radial slots 18 in the bottom and the inverted cup 17 normally rests on the partitions 19 between the slots. The housing 16 and the inverted cup 17 are proportioned so that the cup never completely closes the end 12 of the pipe, and the housing is substantially twice as long as the cup. In the sides of the cylindrical housing there are provided a number of slots 20 that extend downwardly from a point just beneath the roof of the tank. The tops of these slots are always above the highest liquid level.

In order that excessive loss of vapor from the tank will be prevented there is provided a vapor trap 21 mounted near the top of the confined end

12 of the pipe. This vapor trap comprises an inverted cup 22 attached to and concentric with the pipe 10. Within the cup 22 there are provided a plurality of radial vanes 23 extending from the pipe to the sides of the cup 22. These vanes serve to give a large surface upon which vapor arising from the liquid may be condensed, and thus be prevented from escaping from the tank. The condensate on the vapor trap drips back into the tank.

The vent shown is mounted in the roof of the tank near one side of the roof by means of a mounting plate 24 extending from the pipe 10 to the side of the roof and a second mounting plate 25 extending from the cylindrical housing 16 to the side of the roof. The cylindrical housing has a top portion 26 that is bolted to the sides of the cylinder and provided with two handles 27 so that the top may be easily removed for cleaning purposes.

The vent operates as follows: When the space above the liquid in the tank is under pressure greater than atmospheric pressure the roof rises until the liquid level is at the line 28 (Fig. 2). At this point the liquid level is even with the bottom of the inverted cup 17. The vapor pressure thereupon is relieved into the interior of the inverted cup and out the pipe 10. The vapor flowing around and in the vapor trap 21 tends to condense on the radial vanes 23 and the vapor trap cup 22, and this condensate drips back into the tank. Such a construction serves to reduce materially the product loss normally caused by the escape of vapor. When the interior of the tank is under vacuum the roof sinks until the liquid level is substantially at the line 29. Here the movable inverted cup 17 arises within the housing 16 until the bottom of the cup is substantially even with the end 12 of the pipe. This movement of the inverted cup 17 is caused by air pressure operating through the open end 11 of the pipe 10 out into the interior of the inverted cup. As soon as the cup has risen to its proper position the air flows past the bottom of the cup into the interior of the tank and serves to relieve the vacuum. At this point of course the vapor trap is immersed in the liquid within the tank. It can thus be seen that on both pressure and vacuum the vent has a positive action that serves to relieve these conditions promptly.

Having described our invention as related to a typical embodiment of the same, it is our intention that the invention be not limited by details of description unless otherwise indicated, but rather be construed broadly within its spirit and scope as set out in the accompanying claims.

We claim:

1. In a floating roof tank having a roof adapted to float at various heights above the liquid level with varying vapor pressure in a space beneath the roof, a vent comprising: a substantially vertically arranged U-shaped pipe extending through said roof and having an exterior end open to the atmosphere and an interior end located in said space beneath the roof, said pipe having a first portion extending downwardly through said roof, an intermediate portion normally immersed in the liquid, and a second portion extending upwardly to said interior end; an inverted cup over the interior end of said

6 pipe, said cup being mounted for free vertical movement relative to said pipe and to said roof with variations in the height of said roof for limiting the downward movement of said cup to prevent the cup from closing the interior end of said pipe, the lower edge of said cup being normally immersed in the liquid to provide a seal about the interior end of said pipe, said vent being so constructed and arranged whereby a decrease in pressure within said space is adapted to move said cup upwardly relative to the pipe to permit air in said pipe to pass into said space beneath said lower edge and an increase in pressure within said space is adapted to cause the roof to float higher on said liquid to raise the lower edge of the cup above the liquid to permit vapors in said space to enter the pipe.

2. In a floating roof tank having a roof adapted to float at various heights above the liquid level with varying vapor pressure in a space beneath the roof, a vent comprising: a substantially vertically arranged U-shaped pipe extending through said roof and having an exterior end open to the atmosphere and an interior end located in said space beneath the roof, said pipe having a first portion extending downwardly through said roof and a second portion extending upwardly to said interior end; an inverted cup over the interior end of said pipe, said cup being mounted for free vertical movement relative to said pipe and to said roof with variations in the height of said roof above said liquid and means attached to the roof for limiting the downward movement of said cup to prevent the cup from closing the interior end of said pipe, a substantially vertical cylinder formed in said roof and extending therethrough, the end of said cylinder above the roof being closed and the bottom of said cylinder comprising said limiting means and being foraminous and open to the tank below the normal height of the liquid with respect to the roof, said inverted cup being positioned within said cylinder and being free to move relative thereto with its lower edge being normally immersed in the liquid to provide a seal about the interior end of said pipe, said vent being so constructed and arranged whereby a decrease in pressure within said space is adapted to move said cup upwardly relative to the pipe to permit air in said pipe to pass into said space beneath said lower edge and an increase in pressure within said space is adapted to cause the roof to float higher on said liquid to raise the lower edge of the cup above the liquid to permit vapors in said space to enter the pipe.
